UNITED STATES PATENT OFFICE.

FORREST M. PRIESTLEY, OF GRAND RAPIDS, MICHIGAN.

HAND-SLED.

SPECIFICATION forming part of Letters Patent No. 243,971, dated July 5, 1881.

Application filed December 20, 1880. (No model.)

To all whom it may concern:

Be it known that I, FORREST M. PRIESTLEY, of Grand Rapids, in the county of Kent and State of Michigan, have invented a new and 5 useful Improvement in Hand-Sleds; and I do hereby declare that the following is a full, clear, and exact description of the same.

In the manufacture of children's sleds it has been customary to attach an ornament, commonly called a "swan's head," to the forward portion of the runner, to afford means by which the rope is secured to the sled. Such ornamented appendages have always been secured by a screw-bolt or rivet passing through a hole 15 in the ornament and in the runner, and held by a nut or other means. As thus secured the swan's head was easily detached by a comparatively slight side wrench or pressure, because the bolts or screws were liable to twist 20 within a short time and allow the ornament to be entirely detached.

My invention relates to an improved construction of metallic ornaments for hand-sleds, by which the disadvantages before mentioned 25 are completely obviated and the swan's head secured to the runner in a perfectly secure way.

My invention consists in casting the swan's head with a solid-metal arm adapted to pass through the forward portion of the runner and 30 be secured at its opposite end by a bolt, this arm to be used, in combination with cast side pieces, to secure the ornament against the effects of side strain, the whole forming a secure fastening.

35 The accompanying drawings show, in Figure 1, a side view, partly in section; and Fig. 2, a modification.

40 A represents the forward portion of the runner of a sled, and B the forward portion of the rave, these two parts being of the usual or any desired construction.

45 C represents the metallic swan's head or other ornament of like nature. It consists of two arms, 1 2, the arm 1 bearing on the forward portion of the runner, while the arm 2 bears on the upper side of the rave. Represented at 3 is the usual curved portion, to which the cord or rope is attached. The arm 2 is secured by a bolt or rivet passing through 50 such arm and through the rave, as shown.

On the lower end of the arm 1 is arm 4, cast solid with the rest of the ornament, which projects through the opening in the forward end of the runner, and the rear end of this arm may be screw-threaded, if desired, to receive 55 a fastening-nut; or it may be held in any other suitable way. The swan's head is thus connected solidly to the runner without the use of detachable bolts or screws.

Cast solid with the swan's head are plates 60 5, between which the upper portion of the runner, where it is jointed to the rave, fits closely. The purpose of such plates is to prevent the possibility of movement by any force exerted sidewise, and they may be secured to the runner by a nail, 6, if desired. These plates may be constructed as shown in Fig. 1; or they may entirely fill the triangular space between the arms 1 and 2, as shown in the modification in Fig. 2; or they may project from either arm 65 of the ornament. The arm 2, as before mentioned, is secured by a bolt or rivet to the rave. 70

It will thus be seen that there is no possibility of the displacement of the swan's head, since it is connected solidly to the runner by 75 the arm 4, and prevented from having any side movement by the use of the plates 5.

The advantages of the construction in strength and cheapness will be readily appreciated.

Having thus described my invention, what I claim as new, and desire to secure by Letters Patent, is—

1. In combination with a hand-sled, the metallic ornament A, having the arm 4, cast solid 85 therewith, by which it is secured to the runner.

2. The described metallic ornament for hand-sleds, consisting of the curved portion 3, the arms 1 2, the arm 4, and the plates 5, all cast 90 in one piece, as described.

In testimony whereof I have signed my name to this specification in the presence of two subscribing witnesses.

FORREST M. PRIESTLEY.

Witnesses:

CLARK H. GLEASON,
ALVIN B. MOSELEY.
